MEANS FOR EXPANDING PISTONS

August Wiebke, Los Angeles, Calif., assignor to
The Hastings Manufacturing Company,
Hastings, Mich., a corporation of Michigan

Application January 11, 1937, Serial No. 120,028

1 Claim. (Cl. 78—13)

My invention relates to means for expanding pistons for the purpose of making a better fit and eliminating lateral movement or piston slap in the cylinder with its attendant noise and faulty operation.

5 My invention is adapted for use in expanding pistons of all kinds, that is: ribbed pistons, cast iron pistons, steel and other metal pistons, and is applicable to the different parts of the piston 10 so as to expand the piston where needed and to do it under the eye and control of the operator of the machine.

Among the salient objects of my invention are: to provide a means and method for expanding pistons which is simple, economical, efficient and which is under the fullest control of the operator; to provide in an invention of the character referred to means which can be directly applied to any part of a piston and operated to 20 produce any degree or area of expansion needed to put the piston in normal condition; to provide in an invention of the character referred to means for applying to any part of a piston a hammering process of such rapidity and shortness of stroke that it is practically a continuous application of blows or pressures to the surface being treated, as distinguished from blows which leave individual indentations which are clearly visible, in other words, applicant's means produces a smooth surface something after the manner of a rotary planer, the strokes being so rapid and uniform that there is no visible individual indent or depression.

In order to more fully explain my invention, 35 I have illustrated on the accompanying sheet of drawings one practical means for carrying out my new method of expanding pistons and the like, which I will now describe.

Figure 1 is a side elevation of a machine embodying my invention;

40 Figure 2 is a vertical sectional view taken on line 2—2 on Fig. 1;

Figure 3 is a sectional view taken on line 3—3 on Fig. 1;

45 Figure 4 is a plan view, partly in section on line 4—4 of Fig. 2; and

Figure 5 is a view of a piston, showing the hammer in place and indicating the expansion resulting from the action of the hammer.

50 Referring now in detail to the drawing, suitable supporting legs, as 6 and 7 are provided for supporting the mechanism, the legs 1, 1, supporting an electric motor M, the shaft of which is designated 8, and has two universal joints, 9, 9, 55 therein, said shaft 8 having at its operating end

an eccentric cam element 10, supported between the sides 11', 11', on the upper end of an adjustable bracket 11, having a slot 12 therein, through which a screw bolt 13 holds said bracket to the body or frame structure 6', 6', above the 5 legs 6, 6, as seen in Figs. 1 and 2. An adjustment screw 14 operates in the lower end of said bracket 11, and is anchored in a lug extension 15, on the body 6', and is provided with an operating hand wheel 16 at its lower end, whereby 10 the operation of said hand wheel 16 and said screw 14, raises and lowers said bracket 11.

Pivotedly mounted in the upper end of said adjustable bracket 11, between the sides 11', 11', thereof is a hammer operating lever 17, the outer 15 end of which underlies said eccentric cam element 10 and is intermittently depressed thereby as said cam element is rotated by said motor shaft 8. On the underside of the upper end of said adjustable bracket is a downwardly extending 20 tubular portion 18, in which is mounted a plunger 19, normally pressed upwardly by a coiled spring 20, the tension of which is regulated by a screw bolt 21, with lock nut 22 thereon, whereby with every depression of the end of said 25 lever 17, by said eccentric cam 10, said lever is forced upwardly under the tension of said spring 20.

On the inner end of said lever 17 is mounted 30 a hammer element 23, of tapering form, but having a rounded end. Said hammer element 23 is anchored in the end of said lever 17 by its shank portion 23' on which is screwed a nut 24, as indicated in Fig. 5. Said hammer element 23 can thus be adjusted vertically up and down 35 within a piston, indicated C, as illustrated in the drawing.

The upper end of said body or frame structure 6', 6', constitutes an anvil 25, upon which the cylinder or piston C is to be held for treatment, 40 as indicated. Slidably mounted on said body at opposite sides of the anvil portion are two piston holding members 26, 26, connected by an operating screw 27, having right and left hand threads thereon, and operable by means of a 45 hand wheel 28, whereby said holding members 26, 26, are moved together toward and from each other, for centering a piston on the anvil portion of said body and in proper relationship to the hammer element 23. At the left hand side 50 of Fig. 2, in an extension 29 on said body structure, is adjustably held a bearing rod 30, held in adjusted positions by means of a thumb screw 31, for holding the piston C, abutting against it, 55 from moving longitudinally or axially as it is

held in the hand of the operator and turned on the anvil during the operation. This member 30 is an adjustable stop against which the head of the piston C abuts as it is held in position.

5 The anvil portion of the top has at its opposite sides two extensions, as 25', 25', and it is upon and between these extensions that the piston holding members 26, 26, are movably held, a neck portion 26' extending down between said 10 arms or extensions 25', 25', as seen in Fig. 4.

In Fig. 5 is shown a representation of a piston C, showing the hammer element 23 in place therein, above the anvil 25, the short arrows AA and BB indicating areas which have had the 15 treatment with the hammer, while the light broken lines indicate the expansion caused in the piston wall as a result of such treatment. It is understood that the piston wears on the sides opposite each other and at right angles to 20 the sides on which the crank pin bearings are formed, and the operation of the hammer element in the manner herein provided for operates to compress the material in the area being treated so as to cause expansion at the opposite sides 25 from the area being treated.

It is to be understood that this operation is different from so called peening operation in which the hammer used has a round or pointed end and causes a corresponding expansion of 30 the metal in all directions. Applicant's hammer is long and its operation is more like swaging for the expansion is in opposite directions, circumferentially of the piston. The piston is held in place on the anvil and is turned back and forth by hand as the hammer is operated at a 35 very high rate of speed, so that the swaging action or treatment is applied uniformly to the particular area, or to a rib, inside of the piston and in such manner as to produce the desired 40 expansion in the desired place or area on the piston.

The hammer element 23, it is to be noted, is elongated so as to have a work edge extending

axially of the piston and action is more of a swaging action and the metal is compressed immediately above the anvil and expansion caused circumferentially in opposite directions from the area being subjected to the vibrating hammering action or treatment. This vibratory action is such that the surface contacted, as the piston is rotated back and forth by hand, is uniformly compressed and no individual indentations are visible. I have found this method most effective and successful in expanding pistons as and where needed, regardless of the type or material of the piston. 5 10

While I have shown and described one practical means for expanding pistons, I am aware 15 that many changes in the details of construction and arrangement can be made without departing from the spirit of the invention and I do not, therefore, limit the invention to the showing made, except as I may be limited by the hereto 20 appended claim.

I claim:

In a machine for expanding pistons, in combination with an anvil, a hammer supporting member adjustable up and down relative to said anvil, a hammer-operating lever pivotally supported intermediate its ends on said hammer supporting member, a hammer element on one end of said lever, a motor-operated eccentric cam rotatably mounted in said hammer supporting member and positioned to intermittently depress and release the other end of said lever, a spring-actuated plunger carried by said hammer supporting member and acting against the under side of the end of said lever in opposition 35 to the action of said eccentric cam, means for regulating the tension of the spring actuating said plunger, and screw means for adjusting said hammer supporting member and said hammer actuating mechanism as a unit relative to the 40 anvil.

AUGUST WIEBKE.
